UNITED STATES PATENT OFFICE.

ADOLPH GOETTING, OF NEW YORK, N. Y.

DESIGN FOR A BOTTLE.

SPECIFICATION forming part of Design No. 17,222, dated March 29, 1887.

Application filed February 10, 1887. Serial No. 227,218. Term of patent 3½ years.

To all whom it may concern:

Be it known that I, ADOLPH GOETTING, a citizen of Germany, residing at New York, in the county and State of New York, have 5 invented and produced a new and original Design for Perfume-Bottles, of which the following is a specification, reference being had to the accompanying drawing.

The object of this design is to provide a 10 novel perfumery-bottle, as hereinafter described and claimed, reference being made to the accompanying drawing, in which the figure is a perspective view of my design.

In the drawing, the letter H indicates the 15 body of the bottle, having concaved sides A A and rounded top and bottom corners, B B. The upper part of the body is provided with a flat strip, C, having convex ends D and two ornamental bands, F F, around the body and across 20 the top thereof to encircle the same. An ornamental rosette or disk, E, is placed on the

body and overlaps the lower edge of the strip C. The bands F have eyes I, to which are attached a suspending chain or handle, J. The top of the bottle is provided with the cap G. 25

Having thus described my invention, what I claim is—

The design for a bottle having the concaved sides A, top and bottom rounded corners, B, strip C, having convex ends D, bands F, passing up the sides and across the top, disk E, overlapping the lower edge of the strip, and the cap G at the top, substantially as shown and described.

In testimony whereof I have hereunto set 35 my hand and seal in the presence of two subscribing witnesses.

ADOLPH GOETTING. [L. S.]
